UNITED STATES PATENT OFFICE

2,568,899

FRAME

Walter Rambow, Chicago, Ill.

Application July 21, 1949, Serial No. 105,961

6 Claims. (Cl. 40—154)

1

This invention relates to a frame and more particularly to a readily assembled frame for framing objects such as pictures, display cards, advertisements, and the like.

In using advertising signs, such as in store windows and the like, it has been the practice to print such signs upon heavy cardboard or other material and stand the sign in the window. Because of the fact that the signs may be of different sizes it has not been the custom to frame the signs as such practice would require the establishment to maintain a considerable supply of frames of different sizes on hand in order to accommodate the signs. Furthermore, frames of wood or metal construction are expensive, are subject to breakage and on the whole are generally too expensive for everyday use.

I have invented a frame construction which is extremely economical to manufacture and which may be made up as part of the display sign and then folded about the sign to provide a handsome mitered frame which sets off the display sign to its full advantage.

It has often been difficult and expensive to procure frames for snapshots, for picture post-cards worthy of hanging or display, and for other items of a similar nature. The frame construction of this invention may be readily assembled to provide a frame for such items and as a matter of fact may be made up as part of the original card or photograph and folded therearound as hereinafter described to provide a frame for the photograph or card, if such frame be desired. The addition of a frame according to this invention adds very little to the cost of fabrication of the card or photograph and yet provides an item which may be attractively and easily framed at little or no additional expense.

These and other advantages of the invention will be apparent from the following specification and drawings in which:

Fig. 1 is a bottom plan view of one corner of a frame constructed in accordance with this invention;

Fig. 2 is a top plan view partly broken away for clarity of illustration;

Fig. 3 is a top plan view of the frame of Fig. 1 with the sides opened;

Fig. 4 is a sectional view along line 4—4 of Fig. 3;

Fig. 5 is a view of the side of the frame in the process of folding it into position;

Fig. 6 is a view like Fig. 5 after completion of the folding operation;

Fig. 7 is a top plan view of a modified form of the invention;

Fig. 8 is a view like Fig. 7 partly broken away;

Fig. 9 is a top plan view of the corner of the frame with the sides opened;

2

Fig. 10 is a sectional view along line 10—10 of Fig. 9;

Fig. 11 is a sectional view of the side of the frame folded partly into position;

Fig. 12 is a view like Fig. 11 after completion of the folding operation, being a sectional view taken along line 12—12 of Fig. 7;

Fig. 13 is a top plan view of another modified form of the invention;

Fig. 14 is a sectional view along line 14—14 of Fig. 13;

Fig. 15 is a bottom plan view of the device shown in Fig. 13;

Fig. 16 is a view like Fig. 13 partly broken away;

Figs. 17 and 18 are bottom plan views of the device of Fig. 15 showing the method of securing sides of the frame together; and

Figs. 19 and 20 are views showing the frame construction of the invention in opened and folded position respectively and constructed as part of a picture post card or snapshot.

While the invention is susceptible of various modifications and alternative constructions, it is herein shown and will hereinafter be described in its preferred embodiments. It is not intended, however, that the invention is to be limited thereby to the specific constructions disclosed. On the contrary, it is intended to cover all modifications and alternative constructions falling within the spirit and scope of the invention as defined in the appended claims.

Referring now to Figs. 1 to 6 of the drawings, the frame construction comprises a base piece 30 which, in the embodiment shown, is substantially rectangular in shape and upon which may be placed a display sign, photograph, or other item to be exhibited. Secured to each edge of the base piece is a rectangular strip of bendable material. Two of such strips 31—32 are shown, it being understood that a third and a fourth strip are provided along the third and fourth edges of the base piece. Each strip is provided with a first horizontal score line 34 parallel to the adjacent edge of the base piece and a second horizontal score line 35 parallel to the first score line and adjacent the inner edge 36 of each strip. Secured to the inner edge 36 is a strip 37 of reinforcing material provided with a plurality of tongues 38 adapted to fit in slots 39 formed in the base piece.

The strip 31 is provided with a mitered end 40 in order to provide a nicely mitered corner when the strip 31 is folded over the strip 32. In arranging the mitered ends it is possible either to provide one mitered end on each of the four strips about the base piece, or, as preferred, to provide a pair of oppositely facing strips with a miter at each end while leaving the ends of the other

pair of oppositely facing strips straight as shown on strip 32.

To form the frame about the base piece each strip is folded inwardly as shown in Figs. 5 and 6, the strip folding along the score lines 34 and 35 to the point where the tongues 38 may be inserted into the slots 39. When this has been done the frame has the appearance shown in Figs. 1 and 6.

A somewhat modified form of the invention is shown in Figs. 7 to 12, inclusive. In this form, the base piece 50 is also shown as rectangular in shape although it is clear that in any of the forms of the invention the base piece may have as many sides as desired. Strips of bendable material are attached to each edge of the base piece, two of such strips 51 and 52 being shown in the drawings. In this particular embodiment the strips are integrally connected to the base piece. Each strip is provided with a first score line 53 parallel to the adjoining edge of the base piece, a second score line 54 adjacent the inner edge portion 55 of the strip, and a third score line 56 intermediate the first and second score lines. A fastening strip 57 is secured along each edge of the base piece, each fastening strip being so secured that its inner edge 58 is free of the base piece to provide a slot 59 therebetween into which the edge portion 55 may be inserted when the side strips are folded. As in the previous embodiment, the strip 51 is provided with a mitered end 60 to produce a mitered corner as shown in Fig. 7 when the strip 51 is folded over the strip 52. In forming the frame the strip 52 is first folded along its score line with its inner edge 55 inserted in the slot 59 and then the strip 51 is folded along its score lines and its edge portion 55 inserted in a slot 59. The frame so formed has an upstanding outer side 61, a face 62, and an upstanding inner side 63. The card or print to be displayed may be attached to the base piece in any manner such as, for example, sliding its edges into the slot 59 before inserting the edge portions 55 thereinto.

A specific application of the frame of this invention is shown in Figs. 19 and 20 in which a picture post card 70 is provided with four integral strips 71, 72, 73 and 74 of bendable material along its edges. Each strip is provided with a first score line 75 parallel to the edge of the card and a second score line 76 parallel to the first score line and parallel to the outer edge 77 of each strip. Each end of the strips 72 and 74 is mitered as shown at 78 while each end of the strips 71 and 73 is notched as shown at 79 to provide a double miter. In this particular example of the invention, a portion of the material between the score lines 76 and the edges 77 is adapted to be secured to the card which forms the base piece by gluing. To facilitate this, the ends of the strips 71 and 73 are formed so that after the strips 72 and 74 have been folded to the position shown in Fig. 20 and glued in place, the strips 71 and 73 may be folded so that the notched end 79 extends under the miter 78. Thus, they are locked in position and may be glued in such position if desired.

The versatility of the frame construction of this invention is illustrated in Figs. 13 to 18, inclusive. As shown in those figures, the base piece 80 has a width somewhat less than the width of the completed side of the frame. A strip of bendable material 81 is secured to the base piece as is a fastening strip 82. The strip 82 has an edge 83 free of the base piece to form a slot 84 therebetween into which the edge 85 of the strip may

be inserted. As before, the strip is provided with score lines 86 and 87 to facilitate folding of the strip. When folded the strip has an upstanding outer edge 88, a face 89, and an upstanding inner edge 90. At least one end of the adjoining strips is mitered as shown at 91 to provide a mitered corner. It will be noted from the drawings that the base piece 80 extends outward as far as the strip while the fastening strip 82 terminates short of the end of the strip. The mating side piece 94 is so constructed that the fastening strip 82 extends outward to the end while the base piece 80 is short of the end. In order to secure the side pieces together, the fastening strip 82 on the side piece 94 is inserted over the fastening strip on the side piece 92 and the base piece of the strip 92 is inserted into the space under the fastening strip on the side piece 94 and over the inwardly extending edge portion 95 of the strip 96. The side piece when so positioned may be secured by gluing or, if the fit is sufficiently tight, friction alone will suffice to maintain the side piece in position. A display card, such as the card 99, may be glued or otherwise fastened to the bottom of the base piece or, as shown in the drawings, the assembled side pieces may be secured to the card by inserting the edges of the card into the slots 84.

I claim:

1. A side piece for a frame comprising a base piece, a fastening strip secured to the base piece and having one edge free of the base piece to form therewith a slot, a strip of bendable material having one longitudinal edge connected to the base piece, a first longitudinal score line in the bendable strip adjacent said longitudinal edge, a second longitudinal score line in the bendable strip adjacent the other edge of the bendable strip, and a third longitudinal score line in the bendable strip intermediate the first and second score lines, said score lines being parallel to the first mentioned edge of the bendable strip, said bendable strip being adapted to be folded over the base piece and along said score lines with the portion of the bendable strip between the longitudinal edge and the first score line forming an outer side upstanding from the base piece, with the portion of the bendable strip between the first and the third score lines forming a face, with the portion of the bendable strip between the second score line and the third score line forming an inner side substantially parallel to and spaced from the outer side, and with the portion of the material between the second score line and said other edge being adapted to be inserted and frictionally held in said slot.

2. The side piece of claim 1 including means for securing said side piece to a plurality of substantially similar side pieces to form a frame.

3. A side piece for a frame comprising a base piece, a fastening strip secured to the base piece and having one edge free of the base piece to form therewith a slot adapted to receive and frictionally engage a device to be framed, a strip of bendable material having one longitudinal edge connected to the base piece, a first longitudinal score line in the bendable strip adjacent said longitudinal edge, a second longitudinal score line in the bendable strip adjacent the other edge of the bendable strip, and a third longitudinal score line in the bendable strip intermediate the first and second score lines, said score lines being parallel to the first mentioned edge of the bendable strip, said bendable strip

being adapted to be folded over the base piece and along said score lines with the portion of the bendable strip between the longitudinal edge and the first score line forming an outer side upstanding from the base piece, with the portion of the bendable strip between the first and the third score lines forming a face, with the portion of the bendable strip between the second score line and the third score line forming an inner side substantially parallel to and spaced from the outer side, and with the portion of the material between the second score line and said other edge being adapted to be inserted in said slot.

4. A side piece of the character described in claim 3 in which said device to be framed is rectangular and including three substantially similar additional side pieces with the slot in each side piece being adapted to receive an edge of the display to form a rectangular frame about the display.

5. A frame comprising a base piece having a linear edge, a strip-like fastening member secured to the base piece and extending parallel to said edge, said member having an inner edge portion free of the base piece and forming therewith a slot, a strip of bendable material having one edge secured to the base piece, a first longitudinal score line in the strip adjacent said edge, a second longitudinal score line in the strip adjacent the other edge of the material, and a third longitudinal score line in the strip intermediate the first and second score lines, said score lines being parallel to the first mentioned edge of the strip and said strip being adapted to be folded over the base piece and along said score lines with the portion of the strip between the first mentioned edge and the first score line forming an outer side upstanding from the base piece, with the portion of the strip between the first and the third score lines forming a face, with a portion of the strip between the second score line and the third score line forming an inner side substantially parallel to and spaced from the outer side and with the por-

tion of the strip between the second score line and said other edge being adapted to be received in said slot in locking frictional engagement therewith.

- 5 6. A frame comprising a polygonal base piece, a plurality of strips of bendable material, each strip having one edge secured to and extending along a different edge of the base piece and each strip having a first longitudinal score line formed therein adjacent said edge of the strip, a second longitudinal score line adjacent the other edge of each strip, and a third longitudinal score line in each strip intermediate the first and second score lines, a miter formed in at least four strip ends, each of said strips being adapted to be folded over the base piece along said score lines with the portion of the strip between the outer edge of each strip and the first score line forming a side upstanding from the base piece, 10 and with the portion of the strip between the score lines forming a face, to form a frame about the base piece having mitered corners, and a strip-like fastening member secured along each edge of the base piece, each fastening member 15 having an edge free of the base piece, said last mentioned edge forming with the base piece a slot, and each of said slots being adapted to receive the inner edge of a different one of the bendable strips in locking engagement.
